UNITED STATES PATENT OFFICE.

JULIUS D. HAYNSWORTH, OF MANSFIELD, OHIO, ASSIGNOR TO WESTINGHOUSE ELECTRIC & MANUFACTURING COMPANY, A CORPORATION OF PENNSYLVANIA.

ELECTRIC FURNACE.

Application filed March 5, 1923. Serial No. 622,783.

My invention relates to furnaces and particularly to electrically heated resistor furnaces.

The object of my invention is to provide a furnace comprising a plurality of electric heating elements so arranged therein as to uniformly heat material placed in the furnace chamber.

In practicing my invention, I provide a plurality of refractory heat-insulating walls enclosing a furnace chamber. Electric heating elements are located in said furnace chamber supported by the side, end, and top furnace walls. A floor grating is located in said chamber intermediate the top and bottom walls and certain of said heating elements are located in the side and end walls and in auxiliary refractory walls beneath said grating. Refractory reflectors of substantially pyramidal shape are located beneath the grating and reflect the heat from the heating elements located beneath the grating upwardly against the grating and against material located thereon.

The single figure of the accompanying drawing is a vertical sectional view through an electric furnace embodying my invention.

An electric furnace 11 comprises outer side walls 12 and 13, a top wall 14 and a bottom wall 15 which walls may be built up of any suitable refractory heat-insulating material usually employed in the art. An inner lining 16 may be provided and comprises a layer of a suitable high-temperature resisting refractory material or a plurality of bricks or blocks of similar material, usually employed in the art. The hereinbefore mentioned walls are so located and spaced apart as to provide a furnace chamber 17 of any suitable or desired dimensions and contour.

Means for heating the furnace chamber comprise metallic resistor members 18 built up of a number of integral and end-connected, parallel-extending convolutions of a suitable resistor material, such as nichrome. The individual bars may be supported within the furnace chamber 17 by extending through grooves on the inner face of a plurality of refractory bars 19 which are relatively narrow and are spaced apart a suitable distance. The grooved face of the bars 19 is in operative engagement with the inner face of the refractory walls 16 and the bars

are held in their proper operative position 55 by members 21, of substantially T-shape, the inner ends of which extend into the inner lining 16 and may extend into the outer walls hereinbefore described.

The members 21, of T-shape, are located 60 in vertically spaced position, a suitable distance apart, to receive and hold the bars 19, and a suitable number of sets of these members 21 is provided in accordance with the length, width and height of the walls enclosing 65 the furnace chamber and also in accordance with the thickness of the bars constituting the resistor so that the resistor member shall be substantially self-supporting between the refractory supporting bars 70 19. As illustrated in the drawing, heating elements, as hereinbefore described, are located in the top wall or ceiling, in the side and the end walls.

The heating elements hereinbefore described are more particularly disclosed and claimed in a copending application, Serial No. 584,620, filed by T. A. Reid on August 28, 1922, and assigned to the Westinghouse Electric & Mfg. Co.

A floor grating 22 of a suitable skeleton construction is located in a horizontal position in the furnace chamber, intermediate the top and bottom walls of the furnace and serves to support material placed within the furnace chamber to be heat treated therein. Heating elements, as hereinbefore described, are located in the side and end walls of the furnace structure below the floor grating and in this position they will not be subject to drippings from freshly japanued or enamelled articles which may be suspended within the furnace chamber 17 or be located therein supported by the floor grating. I may provide an intermediate refractory 95 column 23 or the column 23 may comprise a short vertical wall extending longitudinally of the furnace chamber, the actual construction employed being entirely dependent upon the size and configuration of the furnace chamber. Heating elements of the kind hereinbefore described are located in or against the vertical surfaces of the wall 23.

In order to reflect the heat generated by the heating elements located below the floor 105 grating against the grating and against material located thereon or suspended thereabove, I provide one or more refractory re-

reflector members 24. The members 24 are built up of a plurality of suitably shaped bricks or blocks of a refractory high-temperature resistor material and the outer reflecting surfaces of the members 24 should be relatively smooth. If the furnace chamber 16 is relatively small and substantially square in horizontal section, the member 24 may be pyramidal in form and substantially 10 square in horizontal section. If one of the horizontal dimensions of the chamber 17 is much greater than the other, it may be necessary to employ an elongated member 24, and a horizontal section therethrough will 15 be substantially rectangular in form. In other words, the object of providing the members 24 is to permit of placing a plurality of electric heating elements below the material-supporting floor of the furnace 20 chamber and of reflecting the heat generated therein against the under surfaces of materials to be heat treated, which are supported on the floor grating or thereabove. While I have shown a reflector having 25 straight sides, I may employ reflector members having curved sides to effect any desired distribution of heat.

It is apparent that fluid japan or vitreous enamel which may drip from the articles 30 to be heat treated or baked, during the initial stages of the heat treatment, would fall upon electric heating elements if they were to be placed in a horizontally-extending position beneath the floor grating, but this action 35 is entirely obviated by locating the heating elements which are placed below the floor grating, in a substantially vertically-extending position and providing a reflecting surface which will reflect the heat generated thereby in an upwardly direction. 40 The reflector members serve also to prevent the respective heating elements located adjacent thereto from radiating heat to one another, thereby tending to reduce the temperature of the heating elements.

45 Various modifications and changes may be made herein without departing from the spirit and scope of my invention, and I desire, therefore, that only such limitations shall be placed thereon as are indicated in the appended claims or are imposed by the prior art.

I claim as my invention:

50 1. In an electric furnace, in combination, a plurality of refractory walls enclosing a furnace chamber, a working floor for said chamber, an electric heating element located below said working floor and means for reflecting the heat from said heating element

upwardly against said floor and against material placed thereon.

55 2. In an electric furnace, in combination, side, top and bottom, refractory walls enclosing a furnace chamber, a working floor intermediate said top and bottom walls, an electric heating element located below said working floor in said side wall, and means for reflecting the heat from said heating element upwardly against said working floor.

60 3. In an electric furnace, in combination, a plurality of side, top and bottom walls surrounding a furnace chamber, a plurality of radiant heating elements supported by one of said side walls in substantially vertical positions, said heaters being substantially co-extensive with said wall, a working floor in said chamber located in a substantially horizontal plane intermediate said top and bottom walls, and means co-operating with the heaters located below said working floor for reflecting the heat generated thereby in an upwardly direction.

65 4. In an electric furnace in combination, a plurality of side, top and bottom walls enclosing a furnace chamber, a plurality of 70 heating elements located parallel and closely adjacent to and supported by each of said side walls, a plurality of heating elements located in substantially vertical positions adjacent to and above said bottom wall and intermediate said side walls, a working floor 75 extending between said side walls and above said intermediate heating elements, and means located between said side walls and said intermediate heating elements for reflecting the heat rays of said intermediate 80 and certain of said side heating elements upwardly against said working floor.

85 5. In an electric furnace in combination, a plurality of side, top and bottom walls enclosing a furnace chamber, a plurality of 90 heating elements located parallel and closely adjacent to and supported by each of said side walls, a plurality of heating elements located in substantially vertical positions adjacent to and above said floor and intermediate said side walls, a working floor extending between said side walls above said intermediate heating elements, and reflectors, of 95 substantially pyramidal form for reflecting the heat of said intermediate and certain of said side heating elements upwardly against said working floor.

100 105 In testimony whereof, I have hereunto 110 subscribed my name this twenty-third day of February 1923.

JULIUS D. HAYNSWORTH.
